UNITED STATES PATENT OFFICE.

ROBERT H. ORR, OF WEOTT, CALIFORNIA.

SAWMILL.

Application filed May 3, 1926. Serial No. 106,481.

My invention relates particularly to sawmills of the type used for sawing railroad ties.

All band mills and sawmills in use at present, waste much motion and energy, mainly because they require two engines, one to haul the log, the other for driving the saw. These old type sawmills are good only for sawing the good lumber off the logs, but can not be profitably adapted for cutting railroad ties or make use of the large quantities of material of inferior quality that remains from the logs after sawing off the good lumber.

My invention eliminates said waste, because it has only one engine; it does not move the log against the saw, but advances the saw against the log, thus eliminating the waste of motion and energy. It is lighter than the old type and more easily transportable.

My invention provides means for cutting timber of any size. It can be used for cutting railroad ties out of the lumber that is wasted at present.

Instead of large, heavy band saws of the old type, in my sawmill small circular saws are used efficiently. My invention performs two cuts at right angles to each other, in one, almost continuous operation. By using this method all vertical grain can be taken out of the timber for flooring.

The advantages over the old type band and saw mills are achieved by the instrumentalities described in the following specification and defined in the claims, and illustrated in the drawings of which

Figure 1 is a side elevation of the sawmill.

Figure 2 is a front elevation of the same.

Figure 3 is a top plan view of the same.

Figure 4 is a fragmentary section taken through the line 4—4 of Figure 2.

Figure 5 is a fragmentary section taken through line 5—5 of Figure 4.

Figure 6 is a fragmentary section taken through line 6—6 of Figure 2.

Figure 7 is a fragmentary view, and

Figure 8 is a fragmentary section through line 8—8 of Figure 4.

The sawmill is supported on stationary frame 9. Two parallel rods 10 and 11 are disposed on each side of frame 9. On the rods 10 and 11 ride rollers 12, which in turn are journalled in shoes 13 which latter

support movable frame 14. Front members 15, 15' of movable frame 14 serve as guides for flanged sleeves 16 and 17, the sleeves being so designed that they provide bearing for mechanisms described later. A stand 18 for the operator is fastened to sleeve 17.

A shaft 19 is disposed at one extreme end of the stationary frame 9, and is supported in bearings 20, as shown in Figure 3. Power is transmitted to this shaft by any conventional means. A pulley 21 transmits power to a pulley 22 by means of a belt 25. Pulleys 22 and 23 are fastened to a shaft 30. The pulley 23 transmits power to a pulley 24 by means of a belt 26. Pulley 24 is mounted on shaft 27 which is supported on bearings in sleeves 16 and 17. A link 28 is pivoted on shafts 19 and 30, while a link 29 is pivoted on shafts 27 and 30. When moving the movable frame towards and away from the shaft 19, the angularity between the links 28 and 29 will be changed, which action makes it possible to change the distance between the shafts 19 and 27 without changing the relative position of the shaft 19 to the stationary frame 9, or the relative position of the shaft 27 to the movable frame 14. Power is transmitted from the shaft 27 to a pulley 31 which is fastened to the shaft 27 by a feather key, the shaft 27 having a long slot 93' so that the pulley 31 can slide laterally on the shaft 27. A belt transmits power from the pulley 31 to the pulley 32 and shaft 33. A pulley 34 on shaft 33 transmits the power through a belt to pulley 35, vertically disposed shaft 36 and to a horizontally disposed circular saw 37 mounted on the shaft 36.

A pulley 38 on shaft 33 transmits power through a belt to pulley 39, shaft 40 and to a vertically disposed saw 41, as shown in Figures 2 and 3. V-shaped slides 43 and 44 are adapted to slide transversely on V-shaped guides 45 and 46, said guides being fixedly supported on the sleeves 16 and 17, as clearly shown in Figure 6. The shaft 36 is supported in bearings in a frame 42 which is pivotally connected at 47 and 48 respectively to the V-shaped slides 43 and 44, as shown in Figures 2 and 3. Vertical members 49, 50 and 51 support the shaft 33, and these members are parts of the V-shaped slides 43 and 44. Shaft 52 is supported on the vertical plates or members 50 and 51. 110

The shaft 40 is supported in bearings in a frame 53 which is pivotally connected to the shaft 52, as shown in Figure 3. A horizontally disposed extension 54 of the frame 42 is 5 connected by a link 55 to a vertically disposed extention 56 of the frame 53; said extension 56 can be moved by a rod 57 which is rotatably supported on plates 58 and 59 which are fixed on the sleeves 16 and 17 respectively. The rod 57 is extended downward, as shown at 60, and held in place by a spring 61. A dog 62 is so placed on the frame 9 that when the frame 14 moves toward the shaft 19, the dog 62 forces the extension 60 to the position shown in dotted lines in Figure 1, thereby through the vertical extension 56 raises the frame 53 around the pivot 52, thus disengaging the circular saw 41, also through the link 55 and the 10 horizontal extension 54 moves laterally the frame 42 around the pivots 47 and 48, thereby engaging the circular saw 37. The dog 63 is so placed on the frame 9 that when the frame 14 moves away from the shaft 19, the 15 dog 63 forces the extension 60 back to the full line position shown in Figure 1, thereby lowering and engaging the saw 41 and laterally disengaging the saw 37. The disk 64 is fastened on the shaft 27 at the end nearest 20 to the operator's stand. The disk 64 is in frictional connection with the disk wheel 65 fastened on a vertically disposed shaft 66 by a feather key 67, the shaft 66 being supported in bearings 68 and 69 on the frame 25 14. The disk wheel 65 is supported on a 30 slidable housing 70, said housing being pivotally connected to a lever 71 which is pivotally connected to a bracket 72, which bracket is fixedly attached to the sleeve 17. 35

40 A drum 73 is attached to the lower end of the shaft 66 carrying a rope 74. Pulleys 75 on the four corners of the frame 9 guide the rope 74, the ends of said ropes being passed through sheaves 76 and 77 which are 45 attached to the shoe 13 of the movable frame 14. The disk 64 is hollow on one side so as to enclose clutch mechanism, as shown 50 in Figure 4. The clutch mechanism comprises a friction wheel 78 which is fastened 55 to the shaft 27. Friction wheels 79 and 80 fasten to shafts 81 and 82 respectively, said 60 shafts 81 and 82 being connected to shafts 83 and 84 respectively by means of universal joints. A bell crank lever 86 pivoted at 87 65 is connected to the shaft 81. A lever 88 pivoted at 87 is connected with a bell crank lever 89 by means of a link 90, the bell crank lever 89 being pivoted at 91 and connected to the shaft 82.

60 The shaft 83 is supported on bearings in sleeves 16 and 17, said shaft 83 being threaded. A nut 92 threadedly engages the shaft 83 and is fastened on the vertical member 49 of slides 43 and 44. A rack 93 is 65 fastened to the member 49. The shaft 84 is

supported on bearings in the sleeves 16 and 17. A bevel gear 94 is keyed to the shaft 84. Gears 95 and 96 are fastened to the shaft 84 and mesh with teeth on the guide members 15 and 15' respectively. Lateral 70 moving of the saws effects movement of the mechanism which includes the rack 93 which meshes with a gear 97, this gear being fastened to a sleeve 98, said gear 97, and said sleeve 98 being freely rotatable on a shaft 75 99. An arm 100 on the sleeve 98 limits the motion of the gear by being blocked by pin 101 which pin may be manually set in one of the circularly placed holes of a plate 102. Plates 102 and 103 are parts of the bracket 80 104 which is fastened to the sleeve 17. The bevel gear 94 meshes with bevel gear 105. The bevel gear 105 is fastened to the shaft 99 which is angularly placed and supported in the bracket 104 so as to enable the operator on the stand 18 to reach and adjust pins 101 and 106 on the circular plates 102 and 103 respectively. A sleeve 107 is keyed to the shaft 99. An arm 108 on the sleeve 107 is blocked by the pin 106 at a preadjusted 90 position, thereby limiting the motion of the gears and the vertical motion of the saws.

My sawmill operates as follows: Power is applied to the shaft 19 and is transmitted to the shaft 27 and disk 64 as described. In 95 neutral position the operator moves the lever 71 which being pivoted to the bracket 72 will move through the sleeve connected to the housing as it raises the housing 70 and the disk 65. Friction between the movable parts will prevent movement until the parts are manually operated. When the disk 65 is at the center of the disk 64, no power is transmitted to the shaft 66. The log to be 100 cut is clamped by any conventional means 105 to the stationary frame in the position shown in dotted lines in Figure 1.

The operator adjusts the pin 106 so as to limit the depth of cut, and adjust the pin 101 so as to limit the width of cut. When 110 power is applied the disk 64 rotates in clockwise direction. When the operator raises the lever 71 above the center of the disk 64, the disk wheel 65 rotates counter-clockwise, and said disk wheel will rotate the drum 73 115 counter-clockwise. The drum 73 winds the rope, exerts a pull on the sheave 76 and releases the sheave 77; the shoe 13 is forced to move on the rollers 12 on the rod 10 toward the shaft 19. The power transmission is 120 not hindered by this motion, because the links 28 and 29 will change their angularity around the pivoted shaft 30. The extension 60 of the rod 57 hits against the dog 62 which forces the extension 60 into 125 the position shown in dotted lines, thereby lowering the horizontal saw 37 and moving it into cutting position, while raising and disengaging the vertical saw 41.

The operator then lowers the lever 71 and 130

adjusts the disk wheel 65 to any distance under the center of the disk 64, thereby advancing the movable frame at an adjusted speed away from the shaft 19.

5 The dotted line position in Figure 1 shows the movable frame and the saws advanced to almost the end of the cut. When the rod extension 60 hits the dog 63, the extension will be forced into the position shown in full 10 lines, thereby engaging the vertical saw 41 and disengaging the horizontal saw 37. Then by raising the lever 71 and the disk 65 above the center of the disk 64, the motion of the frame 14 and the direction of 15 the cut is reversed. These two right angle cuts complete the operation and saw off a railroad tie, or other piece of lumber.

The friction wheel 79 in neutral position does not touch either the inside periphery 20 of the disk 64 or the outside periphery of the friction wheel 78. By moving the lever 86 gear 79 will be brought into contact with the disk 78, it will rotate the shaft 83, thereby moving the nut 92, plate 49, and slides 25 43 and 44 on the guides 45 and 46, the rack 93 moving with the slides will rotate the gear 97 and sleeve 98 until the arm 100 hits the pin 101 when the friction wheels 78 and 79 will slip. The operator can also manually 30 disengage the friction wheels 78 and 79 when the circular saws reach laterally the desired width of the cut.

The friction wheel 80 is engaged with the friction wheel 78, or the disk 64 by the lever 35 88, link 90 and crank lever 89. The shaft 84 rotates the gears 95 and 96, said gears moving on the rack part of the guides 15 and 15'. Raising or lowering the sleeves 16 and 17 and all mechanism supported on said 40 sleeves, thereby raising or lowering the circular saws.

The shaft 84 also rotates the gear 94, gear 45 105, shaft 99, sleeve 107, arm 108 until said arm is stopped by the pin 106. This motion also can be manually regulated by disengaging the friction wheel 80 through lever 88 when the circular saws are adjusted to the desired depth of cut.

The dogs 62 and 63 may be adjusted to 50 any length of cut by moving them to another point on the stationary frame.

Although I have shown and described one embodiment of my invention, it is to be understood that the same is susceptible of various changes; and I reserve the right to employ such as may come within the scope of the appended claims.

I claim:

1. In a sawmill a saw-carrying frame so 60 mounted with reference to the work that one is movable with respect to the other for mak-

ing a saw cut, a pair of saws carried by said frame and having their cutting planes extending transversely to each other, means controlled by the relative travel of the saw 65 frame and work to make the saw cut, for automatically moving one of said saws into cutting position and the other into inoperative position before the saw enters the work in one direction and for reversing said position of said saws when the travel relative to the work is reversed.

2. In a sawmill, a frame so mounted with reference to the work that one shall be movable with reference to the other to make a 75 saw cut, a pair of saws having their cutting planes extending transversely of each other, a saw-carrying frame supporting said saws and being movable in two directions, each transverse to said first named frame for adjustment of the saws, but in the plane of the operation of one or the other respectively of the saws, and means for simultaneously moving one of said saws into cutting position and the other out of cutting position. 85

3. In a sawmill, a frame so mounted with reference to the work that one shall be movable with reference to the other to make a saw cut, a pair of saws having their cutting planes extending transversely of each other, a saw-carrying frame supporting said saws and being movable in two directions, each transverse to said first named frame for adjustment of the saws, but in the plane of the operation of one of the saws, means for 95 simultaneously moving one of said saws into cutting position and the other out of cutting position, and means for limiting the movement of said saw-carrying frame into adjusted position. 100

4. In a sawmill, a frame so mounted with reference to the work that one shall be movable with reference to the other to make a saw cut, a pair of saws having their cutting planes extending transversely to each other, a frame for supporting both saws and being movable in two directions, each transverse to the first named frame but in the plane of the operation of one or the other respectively of the saws, means for causing relative movement by said first-named frame and the work for causing the saws to cut from end to end of the work, means for simultaneously moving said saws one into operative position and the other into inoperative position during one relative movement of the work with respect to said first named frame and vice versa during the opposite movement of the work, and manually controlled means for moving said saw-carrying frame for adjusting said saws to cut at different places. 115 120

ROBERT H. ORR.
